UNITED STATES PATENT OFFICE

CHARLES W. MEVES, OF SHEBOYGAN, WISCONSIN, ASSIGNOR TO SHEBOYGAN COUCH COMPANY, OF SHEBOYGAN, WISCONSIN, A CORPORATION OF WISCONSIN

BED DAVENPORT

Application filed February 27, 1928. Serial No. 257,241.

The invention relates to davenport and more particularly to that type of davenport convertible into a bed.

An object of the invention is to provide, in 5 that type of bed davenport including an invertible seat member, an improved form of linkage which affords simplicity, compactness and rigidity of construction, the linkage being of such character as to afford a rigid, 10 mutual support for the bed members of the davenport when they are extended to bed-forming position, and suitable provision being made for insuring against the collapse of the rear portions of the elevated bed.

15 Another object of the invention is to provide spring means acting on swinging supports for the invertible seat member to facilitate manipulation of the linkage and to insure proper folding and unfolding of the linkage.

A further object of the invention is to perfect details of construction generally.

The invention further consists in the several features hereinafter set forth and more 25 particularly defined by the annexed claims.

In the accompanying drawings, Fig. 1 is a transverse sectional view of a bed davenport embodying the invention;

Fig. 2 is a fragmentary transverse sectional view taken along the line 2-2 of Fig. 1;

Fig. 3 is a transverse sectional view of the davenport, similar to Fig. 1, but showing the operating parts in an intermediate passing position;

Fig. 4 is a transverse sectional view of the davenport as it appears when converted into a bed; and

Fig. 5 is a fragmentary detail plan view of part of the davenport when in bed-forming position.

In these drawings, the numeral 10 designates one of a pair of spaced end frames, the other not being shown, but both connected to a fixed back 11.

45 A pair of mounting plates 12 are secured

to the opposite end frames 10 by means of screws 13 receiving wing nuts 13', or by means of other suitable fastening elements, and all the moving parts of the davenport are carried by these plates which may readily be attached to the davenport.

50 A fixed front rail 14 extends between the end frames 10 and abuts at each end against a flanged portion 15 of each mounting plate 12 to which flanged portion the front rail 55 is secured by screws 16. At each end of the davenport, a hook-shaped arm 17 is pivotally mounted at its lower end on a pin 18 secured to each mounting plate 12 behind and adjacent the lower parts of the front rail.

55 The upper forwardly projecting ends of the arms 17 are pivotally connected by respective pins 19 to flanges or ears 20 formed integrally with the opposite end portion of a horizontally-disposed angle member 21 extending longitudinally of the davenport.

60 A U-shaped frame member 22 of angle cross-section has its ends secured to the angle member 21 near the ends of the latter to form a rectangular seat frame to the outer flanges of 70 which are secured surrounding wooden strips 23 for facilitating upholstering. The ends of the angle member 21 extend beyond the ends of the angle member 22 in order that the hook-shaped arms 17 will clear the 75 wooden strips 23 at the ends of the seat frame, and in the seat-forming position of Fig. 1, the lower edge of the forward wooden strip 23 lies close to the upper edge of the fixed front rail 14.

80 The seat frame has mounted thereon two sets of upholstery springs 24 and 25 which project from opposite faces of the frame. The springs 24 constitute part of the seat upholstery and have placed thereabove seat 85 cushions 26 which may be of the removable and reversible type, while the coiled springs 25 on the other face of the seat frame form part of the upholstery of a bed section 27, as hereinafter described. When a box seat 90

is desired the covering of the permanent cushion may be attached directly to the wooden strips 23.

On the pivotal connections 19 between the seat frame and the hook-shaped arms 17, the seat member may be inverted from its seat-forming position, shown in Fig. 1, to its bed-forming position, shown in Fig. 4, the shape of the swinging arms 17 providing the necessary clearance for the inversion of the seat. When in the position shown in Fig. 1, the sides of the seat frame adjacent its rear portions rest on brackets 28 secured to the end frames 10, and the swinging arms 17 are limited in their backward movement by their respective engagement with pins 32 secured to the upper portions of the mounting plates 12. At each side of the davenport, a coiled spring 34 in tension has its upper end anchored on the pin 32 and its lower end anchored on the rear end of a bar 35 secured to and projecting rearwardly from the lower portions of the swinging arm 17, thereby urging the bar upwardly to exert a forward thrust on the arm 17. A bed section 36 includes an angle frame 37 similar to that of the seat frame and has secured thereto a set of upholstery springs 38. The forward portions of the bed frame 37 have upstanding brackets or plates 39 secured thereto, one at each end of the frame, and each of a pair of crossed links 40 has a pivotal connection 41 at one end with each bracket 39. The other end of each link 40 has a pivotal connection 42 with one of a pair of brackets or plates 43 fixedly secured to the opposite end portions of the seat frame and adjacent the pivotal connections 19 for the seat-supporting arm 17. The crossed links 40 are disposed on opposite sides of their brackets 39 and 43 and bear laterally against the brackets. In the seat-forming position of the davenport shown in Fig. 1, the bracket 43 depends from the seat frame. The crossed links 40 pivotally connecting these brackets are of substantially the same length but are so related that the forward pivotal connection 41 on the bracket 39 of the bed frame 37 is at a lower elevation than the other pivotal connection 41, while at the seat frame bracket 43 the forward pivotal connection 42 is spaced above the other. The pivotal connections 42 are at regions somewhat below and to the rear of the pivotal connection 19 on each seat-supporting arm in the seat-forming position of the davenport, so that upon the inversion of the seat member the links 40 will be both lifted and drawn forward.

The rear portion of the bed frame 37 carries aligned pins 44 at its opposite ends on which legs or links 45 are each pivotally mounted at an end portion. The other end portion of each leg or link 45 carries a pin 46 which is slidably mounted in a horizontally disposed slot 47 formed in a horizontal bracket 48 secured by screws 49 or other suit-

able fastening means to the lower and rearward portions of each mounting plate 12. A swinging strut 50 has one end pivotally connected by a pin 51 to each leg 45 at an intermediate point on the leg near the pivot pin 44, and the other end of the strut 50 is pivotally mounted on a pin 51 secured to the mounting plate 12 at a point forward of the bracket 48 and slightly above the plane of the slot 47. The legs or links 45 serve to support the rear part of the bed when the seat is inverted, as seen in Fig. 4 in which position the pivotally-mounted struts 50 hold the link in a vertical position. The seat member when inverted to bed-forming position is supported in part by the usual folding legs 52 which are swung down from the outer portion of the inverted seat frame to prevent tipping of the bed. The bed-supporting legs 45 and their connected struts 50, all formed of flat metal bars, are provided with suitable offsets, as best seen in Fig. 5, to provide operating clearance.

In order to support the rear bed section 36 from the floor when it is stored beneath the upright seat, an angle bracket 53 is secured to each end of the frame 10 adjacent the rear end of the rear bed section to receive the lower edge of the bed section frame 37. The brackets 53 limit the downward movement of the rear bed section to a point spaced a suitable distance from the floor and also form supports on which the bed section frame may slide and pivot during the manipulation of the linkage.

To change the davenport from the seat-forming position of Fig. 1 to the bed-forming position of Fig. 4, the operator grasps the rear portion of the seat member and draws it forwardly and upwardly, a passing position of the moving parts being shown in Fig. 3. On the first part of the upward movement of the seat member, the seat-supporting arms 17 swing forwardly towards the fixed front rail 14 under urge of the coiled springs 34 which assist this movement. The arms 17 are limited in their forward travel by their abutment with the flanges 15 of the mounting plates 12, and the pivot pins 19 on the forwardly projecting portions on the arms assume positions forward of the fixed front rail. During this movement of the seat-supporting arms 17, the pivot pins drop no substantial distance in elevation. Simultaneously with the initial movement of the seat member, the forward portion of the bed frame 37 is lifted by the links 40, the rear portion of this frame pivoting momentarily on the bracket 53 until the bed-supporting legs or links 45 pass over center with respect to the struts 50. As soon as such point is reached the action of the crossed links 40 is to lift the rear bed section 36 in a substantially horizontal position until the bed-forming position of Fig. 4 is reached.

During this upward movement of the rear bed section, the pins 46 at the ends of the legs or links 45 travel rearwardly in the slots or tracks 47 formed in the bracket 48 and finally reach positions at the rear ends of these slots, at which point the bed-supporting legs or links assume a vertical position as seen in Fig. 4. In this position of the legs the struts 50 prevent accidental forward displacement of the pins 46 at the lower ends of the bed-supporting legs to insure against collapse of the rear bed section. In the bed-forming position of the davenport, as seen in Fig. 4, the crossed links 40 connecting the brackets 39 and 43 on the rear and front bed sections, respectively, are disposed in such relation that they rigidly brace the rear bed section from the forward bed section against either upward or downward movement, one of these links forming a tension member while the other simultaneously forms a compression or strut member. The lateral abutment of the links 40 with opposite sides of the brackets 39 and 43 serves to avoid any undesirable side play between the bed sections. The pivotal connections of these links with their brackets, however, permit the smooth folding and unfolding of the linkage and provide a supporting means whereby the rear bed section is raised or lowered in a substantially horizontal disposition. When the seat member reaches its inverted position the folding legs 52 carried by the seat frame are swung down as seen in Fig. 4 to prevent tipping of the completed bed. Bedding 55, which may include a hinged mattress, is placed above the coiled springs 25 and 38 of the bed sections, and may, if desired, be fastened to the bed sections in order that it may fold and unfold with the davenport.

To return the parts from the open position of Fig. 4 to the closed position of Fig. 1, the supporting legs 52 are swung back to folded position along the seat frame and the movements of the seat member are reversed, the seat frame being lifted and swung upwardly while the bed frame 37 simultaneously descends to a position behind the front rail. During this initial lifting movement of the inverted seat frame, the seat-supporting arms 17 are retained in their forward position by the tension of the springs 34 and the links 40 are urged rearwardly which causes the rear bed section to be also urged rearwardly simultaneously with its downward movement. The rearward displacement of the bed section causes the bed-supporting legs or links 45 to pivot on the pins 51 on the ends of the struts 50, thereby causing the pins 46 at the lower ends of the legs 45 to move forwardly in the slots 47. As the linkage folds further from the position shown in Fig. 3, the further descent of the bed section causes the rearward movement of the seat-supporting arms 17 simultaneously

with the lowering of the seat frame to its seat-forming position, the seat-supporting arms being limited in their rearward movement by their abutment with the stop pins 32. In this position of the linkage, the rear portions of the seat frame rest on the brackets 28, while the rear bed section is suspended on the links 40 and rests on the angle brackets 53. In the seat-forming position of the davenport, the bedding is folded in the space between the bed sections. During the folding operation the retractile springs 34 retard the downward movement of the seat frame and bed frame to insure smooth operation, and the travel of the legs 45 in the slots 47 serves to minimize the rearward movement of the bed frame.

The longitudinal axes of the crossed links 40 remain in crossed relation in the entire travel of the seat member from its seat-forming position to its inverted bed-forming position, thereby enabling the bracing effect of the links to be attained when the parts are in their bed-forming position and also preventing binding of the linkage in any position of the linkage.

The invention provides a davenport including a simple but effective type of linkage which provides rigid construction, compactness and smooth operation.

What I claim as new and desire to secure by Letters Patent is:

1. In a bed davenport, the combination of a seat member invertible to bed-forming position, swinging supporting arms on which said seat member is pivoted for inversion, a bed member having an articulated connection with said seat member for movement to elevated bed-forming position upon the inversion of said seat member, a stop member limiting the rearward movement of each supporting arm, and a retractile coiled spring anchored at its upper end on said stop member and at its lower end on the lower portions of the adjacent supporting arm for urging said arm to a forward position upon the inversion of said seat member and for retarding the return movement of said supporting arm during the subsequent movement of the seat member to its seat-forming position.

2. In a bed davenport, the combination of a seat member invertible to bed-forming position, supporting means for said seat member including supporting plates and swinging arms pivotally mounted on said plates and on said seat member, a bed member having an articulated connection with said seat member to lie below said seat member when the latter is in seat-forming position and to be lifted by said connection into elevated bed-forming position upon the inversion of said seat member to bed-forming position, a bracket secured to each of said supporting plates and having a substantially horizontal

slot, a link member pivotally secured to said bed member to extend therebelow in substantially upright position in the elevated bed-forming position of said bed member and said link member being connected to said bracket for sliding travel in said slot, and a strut member pivotally mounted on said supporting plate forwardly of said slot and having a pivotal connection with an intermediate portion of said link member whereby to brace said link member in its bed-supporting position.

In testimony whereof I affix my signature.
CHARLES W. MEVES.
